[57] CLAIM

The ornamental design for an ornamental hairband or similar article, substantially as shown and described.

DESCRIPTION

FIG. 1 is a perspective view of an ornamental hairband or similar article showing my new design, the broken lines indicate environmental structure and form no part of the claimed design;

FIG. 2 is a perspective view in a different position of use, the broken line showing of a hand and portion of an arm indicates environmental structure and forms no part of the claimed design;

FIG. 3 is a side elevational view thereof; and

FIG. 4 is a top plan view thereof.

FIG. 1

FIG. 2

FIG. 3

FIG. 4
